Attorney

UNITED STATES PATENT OFFICE

WILLIAM S. KIRKPATRICK, OF BERGHLZ, OHIO

JOIST AND RAFTER JACK

Application filed September 12, 1929. Serial No. 392,119.

The invention relates to a device to be used for straightening crooked joists or rafters when laying the flooring or roofing boards, and has for its object the provision of a jack 5 adapted to straddle adjacent joists or rafters to straighten them while the flooring or roofing is being attached thereto and consists of a lever member and pulling members pivotally secured thereto having open ends to engage 10 over adjacent joists or rafters, one of the pulling members being elongated to rest upon the adjacent joists or rafters to hold the jack properly positioned, the lever member and pulling members being provided with a 15 series of openings to receive the pivot pin and sliding means by which the device may be adjusted for joists and rafters spaced at varying intervals, and also to adjust the pull of the lever to suit the conditions under 20 which the tool is used.

The invention will be described in detail hereinafter and will be found illustrated in the accompanying drawings in which

Figure 1 is a top plan view of the improved 25 joist or rafter jack showing and jack resting on adjacent joists or rafters shown in broken lines and fragmentarily,

Figure 2 is a side view in elevation, and

Figure 3 is a transverse sectional view on 30 a plane indicated by the line 3—3 of Figure 1.

In the drawings similar reference characters are used to designate corresponding parts throughout the several views.

The improved joist or rafter jack includes 35 a lever member 1 provided with a series of openings 2 in one of its ends, and pulling members 3 and 4 suitably secured to the lever member 1 by means of pivot means 5 engaging through selected openings 2 in the lever 40 member 1, and selected openings 6 in the pulling members 3 and 4, said members 3 and 4 each having a series of openings 6. The member 3 is elongated, and has the openings 6 arranged substantially midway of its length 45 so that said member 3 rests upon and is supported by the joists or rafters A when the device is in position for operation, and each of the members 3 and 4 have downturned hook members 7 to engage on the remote sides 50 of the joists or rafters A, the construction

shown in the form selected for illustration disclosing the members 3 and 4 made of straps of iron or steel and having the terminals on which the hook members 7 are formed given a half turn as shown at 8.

In operation, it will be apparent that when it is necessary to straighten crooked joists or rafters when laying flooring boards or roofing boards, the jack is engaged with the joist or rafter requiring straightening and the adjacent joist or rafter is in the position shown in Figure 1, and then by swinging the lever member 1 to reduce the distance between the hook members 7, it will be apparent that the crooked joist or rafter will be straightened to hold it while the flooring boards or roofing boards are secured thereto.

What is claimed is:—

1. A joist and rafter jack, comprising a lever member, and pulling members pivotally engaging the lever member and provided with hooked ends to engage adjacent joists or rafters, one of said pulling members being extended beyond the pivoted portion to provide an extended member to support the members on the joists or rafters.

2. A joist and rafter jack, comprising a lever member, pulling members, said lever member and pulling members having series of openings therein, pivot pins engaging through selected openings in said members and pivoting said pulling members on said lever member, one of said pulling members being of a length to rest upon adjacent joists or rafters to support the members thereon.

In testimony whereof I affix my signature.

WILLIAM S. KIRKPATRICK.
